TYPE-WRITING MACHINE.

1,028,922.

Specification of Letters Patent. Patented June 11, 1912.

Application filed May 27, 1911. Serial No. 629,795.

To all whom it may concern:

Be it known that I, JOHN WALDHEIM, citizen of the United States, and resident of Newark, in the county of Essex and State 5 of New Jersey, have invented certain new and useful Improvements in Type-Writing Machines, of which the following is a specification.

My invention relates to ribbon mechanism for typewriting machines and its general object is to provide improved mechanism of the character specified.

More specifically the object of my invention is to provide novel devices for doing 15 two-color and mimeograph work with facility and despatch.

Another object is to provide improved ribbon spools.

To the above and other ends my invention 20 consists in the features of construction, arrangements of parts and combinations of devices to be hereinafter described and particularly pointed out in the claims.

In carrying out my invention in the present instance, I provide two vibrators or vibratory ribbon guides or carriers arranged one behind the other and adapted to be separately vibrated at will by devices actuated from the printing keys. A two-color 25 or other character of ribbon passes from one ribbon spool horizontally through the guiding slots in one vibrator, and then is guided downward at an angle over a guiding device or turning bar and thence upward at a 30 corresponding angle to the other vibrator, passing horizontally through the slots therein and thence to the other ribbon spool. By thus guiding the ribbon in triangular fashion, its horizontal printing portions 35 present opposite edge portions, fields or colors of the ribbon to the printing point when the vibrators controlling these opposite edge portions are operative; also the actuating devices are adapted to be readily 40 disconnected from both vibrators so that neither horizontal printing portion of the ribbon will be presented to the types, thus facilitating the preparation of mimeograph or stencil sheets.

50 My invention will be more fully described in connection with the accompanying drawings, wherein—

Figure 1 is a vertical front to rear sectional view of a Monarch typewriting ma-

chine embodying my invention. Fig. 2 is a 55 top plan view of a ribbon spool flange. Fig. 3 is a front elevation of the ribbon vibrator. Fig. 4 is a fragmentary front elevation showing the upper part of said machine and the ribbon vibrating and guiding devices. 60 Fig. 5 is a detached perspective view of the guide for the ribbon vibrators. Figs. 6 and 7 are operative views of the ribbon vibrators showing respectively the rear and front vibrators in operated positions. Fig. 8 is a 65 plan view partly in section of the ribbon operating lever and vibrators. Fig. 9 is a fragmentary view of a paper ribbon.

As shown in Fig. 1 the main frame of the machine comprises a base 1, posts 2 and a 70 top plate 3. Key levers 4 are fulcrumed on a plate 5 in the rear part of the base, each key lever being provided with a restoring spring 6 and having pivoted to it at 7 a sub-lever 8, said sub-lever being slotted at its 75 lower end to coöperate with a fixed abutment 9 and having its upper end connected by a link 10 to a type bar 11 pivotally supported on a hanger 12 secured to a segment 13 which is adapted to shift to change case in 80 the usual or any other suitable way. The type bars when actuated coöperate with the front face of a rotary platen 14 supported on a platen frame or carrier comprising end bars 15 and also a connecting slide bar 16 85 which is grooved at its upper and lower faces to coöperate with anti-friction balls 17, said balls also coöperating with fixed grooved track-ways 18 secured to standards 19 rising from the top plate. The platen carrier is 90 connected by a strap 20 with a spring drum or power device 21 which constantly urges it leftward, the leftward or letter spacing movements of the carrier being controlled by escapement devices of the usual sort (not 95 herein shown), certain of said devices being connected by a link 22 with the central arm 23 of the universal bar frame which further comprises a rock shaft 24 pivoted in the base 1, said frame carrying a universal bar 25 100 which underlies the key levers. The universal bar frame is provided with the usual restoring spring 25^a, said spring also serving as a restoring spring for the vibratory ribbon devices hereinafter described.

As herein shown a ribbon 26, divided longitudinally into fields *a* and *b* of different colors or characteristics is supported on

horizontal ribbon spools located one at each side of the machine and forward of the platen. Each ribbon spool comprises a core 27 and upper and lower flanges 28 and 29. 5 The ribbon spools are preferably of the ordinary Monarch construction except that the upper flange of each spool is formed with an integral circular raised portion 30 which is cupped out or depressed to provide 10 a finger piece or button by which the spool may conveniently be rotated. The ribbon spools are supported at the upper ends of shafts 31 which at their lower ends carry beveled pinions 32 constantly meshing with 15 beveled pinions 33 at the forward ends of horizontal shafts 34. Each shaft 34 carries at its rear end a beveled pinion 35 which is adapted to mesh with an actuating pinion 36 secured to a driving or power shaft 37 20 connected by devices comprising intermeshing pinions 38 and 39 with the spring drum 21 in such wise that during leftward letter space movements of the carriage the shaft 37 will be automatically rotated. Said shaft 25 is movable endwise to connect the pinions 36 in alternation with their coöperative pinions 35 so as to turn the ribbon spools alternately to wind the ribbon back and forth. 30 Novel vibrating devices are provided for moving the printing portion of the ribbon up and down at printing operation, said devices comprising two parallel ribbon vibrators, carriers or guides numbered respectively 40 and 41, said vibrators being plate-like in form and the vibrator 41 being arranged behind the vibrator 40 on a stationary guide which comprises uprights 42, a connecting cross bar 43 and lateral ears 44 (Fig. 5) which ears are secured by screws 45 to the top plate of the machine. The uprights 42 are provided with sets of parallel grooves 46 and 47, the grooves 46 receiving the side edge portions of the vibrator 40 45 and guiding and controlling said vibrator both while it is stationary and during its up and down movements; and the grooves 47 co-operating likewise with the vibrator 41. The body portion of the vibrator 40 is provided 50 at its edges with shoulders 40^x which normally rests on the tops of the uprights 42, serving as stops to limit the downward movement of the vibrator and also maintaining it in normal position. The vibrator 55 41 is similarly provided with arresting shoulders 41^x. These shoulders maintain the vibrator so that the printing portions of the ribbon never drop as low as the tops of the uprights 42, catching of the ribbon 60 during vibration being thus avoided.

The vibrators 40 and 41 are of like construction but are oppositely turned or faced. The vibrator 40 is shown detached in Fig. 3 from which it will be seen that the vibrator is plate-like in form and has an upward

extension 48 formed with a guide slot 49 having a side opening to permit the entrance of the ribbon. Said vibrator has also a lateral and inclined extension 50 at the right-hand side provided with an inclined guide slot 51 also having a ribbon opening. Centrally the body of the vibrator is formed with a vertical slot 52 which is widened at its lower end, providing a horizontal shoulder 53. At the lower end the 75 vibrator 40 is cut away as indicated at 54.

Referring to Figs. 4, 6 and 7 it will be observed that the rear vibrator 41 is similar in construction to the vibrator 40 but is turned oppositely or back to back to said 80 vibrator 40 so that the corresponding lateral extension 50^a and inclined guide slot 51^a are at the left instead of at the right as in the case of the vibrator 40. Furthermore, the extension 48^a and the vertical guide slot 85 49^a are at the left, instead of at the right as are the corresponding extension 48 and slot 49; while, the shoulder 53^a formed in the slot 52^a is at the left, instead of at the right as in the case of the shoulder 53. Also, the 90 lower portion of the ribbon vibrator 41 is cut away as indicated at 54^a. The ribbon is guided through these devices in a novel way presently to be described. Said devices are 95 adapted to be vibrated by devices comprising a two-part operating lever. The forward part of said lever projects through a slot or opening 55^a in the usual central front plate 55 and comprises a finger 56 which projects through the slots 52 and 52^a so that its front end may readily be grasped and manipulated. Said finger 56 extends rearward and divides into two branches 57 which, as shown in Figs. 1 and 8, are curled around the end portions of a pivot pin 58, said pin being secured to the forward end of the main part of said operating lever, said curled end being embraced between the branches 57. Said main part is divided into two angularly disposed branches 59 and 60. 100 The branches 59 and 60 extend laterally away from each other back of the curled end, as appears from Fig. 8, and are pivoted on screws 61 secured in a lug 62 depending from the top plate. Back of the pivot 61 105 the branch 60 is extended rearward as indicated at 60^a and also off-set to the median plane of the operating lever. The finger 56 is provided with a rearward extension 56^a which is provided with an angular end portion 56^b, the upper edge of which is formed with V-notches 63, 64 and 65, said notches being adapted to coöperate with the branch 60 of the main part of the operating lever to hold the forward swinging part of 110 said operating lever in one or another of three predetermined relationships with said operating lever.

The two parts of the operating lever are 115 adapted to be vibrated as a single piece or 120

lever at printing operation by an upright link connected to the extension 60^a at 66. The upper portion 67 of said link is detachably connected to the body portion 68 of said link, the upper end of said body portion being threaded to coöperate with a tapped hole in the portion 67, the construction enabling the relationship between the link and the operating lever to be varied. The power 10 end of the main part 68 of the link is pivotally connected to the central arm 23 of the universal frame and receives motion therefrom, transmitting the motion to the operating lever. Said link also transmits motion 15 to a ribbon guide or turning bar device through an arm 69 which is adjustably secured between the nuts 70 on the link 68. The arm 69 curves upward and forward and is provided with a lateral stud 71 which 20 operates with a slot 72 in the rear arm of a lever 73 fulcrumed at 74 to a bracket 75 secured to the under side of the top plate. The forward arm of the lever 73 projects through the slot 55^a and terminates in a 25 broadened upturned portion 76 formed with a horizontal slot 77 having an opening for the ribbon, the part or device 76 constituting a ribbon guide or turning bar.

Referring now to the course of the ribbon 30 through the vibrators, the ribbon 26 as it leaves the left-hand ribbon spool has uppermost the field *b* which may, for example, be the red field, and said ribbon passes from said spool inward toward the vibrators, entering the slot 49 in the vibrator 40 as perhaps appears most clearly from Fig. 7, thence extending horizontally over the front of the extension 50 and through the inclined slot 51, thence turning downward at an 35 angle behind the extension and in front of the vibrator 40 to the turning device 76, passing behind said turning device and forward through the guide slot 77, thence upward and leftward to the inclined slot 51^a 40 of the vibrator 41, passing behind the extension 50^a as perhaps appears most clearly in Fig. 6, and then horizontally rightward over the extension 48^a and backward through the slot 49^a, passing from behind the extension 45 rightward to the right-hand ribbon spool.

For the sake of clearness the course of the ribbon has been followed from the left-hand ribbon spool through the front vibrator 40, and thence over the guide 76 to the rear vibrator, then to the right-hand ribbon spool. It is, however, to be understood that the most convenient way of threading the ribbon is to first insert it into the guide slots 50 55 and then to pass the folds oppositely through the rear and front vibrators. It will be found in practice that it is immaterial whether the ribbon is introduced into the guide slots 77 with the field *b* at the left 60 as shown, or with the field *a* at the left. In

either case one of the vibrators will present the ribbon field *a* to the types and the other vibrator will present the field *b*, while the finger 56 will be found to act properly as an indicating device under all conditions. 70 From a consideration of Figs. 4, 6 and 7 it will be observed that by reason of the triangular fashion in which the ribbon is threaded through the two vibrators, said ribbon will be turned so that whereas on the 75 left-hand spool the ribbon field *b* is uppermost, on the right-hand ribbon spool the ribbon field *a* is uppermost; and whereas at the printing portion of the ribbon controlled by the vibrator 40, (that is, the horizontal portion or ply between the slots 49 and 51) the upper field *b* is uppermost, in the horizontal ply or printing portion of the ribbon controlled by the vibrator 41 the ribbon field *a* is uppermost. The ribbon is broken away 80 in Fig. 4 so as clearly to show that the horizontal plies or printing portions controlled by the ribbon vibrator are practically in register but with the difference that the printing fields are inverted. Moreover, the 85 horizontal printing plies are oppositely faced, that is, considering the front of the forward ply to be the face of the ribbon, then the front of the rear ply is the back of the ribbon. 90

It will be apparent that the construction and arrangement is such that if the vibrators be vibrated separately and to an extent sufficient to bring only the upper portion of the ribbon opposite the printing point there 95 will result a variation in the color or character of the printing since when the vibrator 40 is in operation the upper printing field *b* will be presented to the types while when the vibrator 41 is in operation the ribbon 100 field presented to the types will be the upper field again, but the upper field in this case will be the ribbon field *a*. The extent of vibration is so limited that one vibratory ribbon part is never vibrated entirely above 105 the other, thus avoiding the catching of one on the other. It will be further understood that the vibrators are rendered operative by switching the forward portion or finger 56 to engage with one or another of the shoulders 53 and 53^a, the finger being adapted to 110 underlie said shoulders and fit into the spaces between said shoulders and the bottoms of the slots. For example, as appears in Fig. 4, the finger 56 underlies the shoulder 53^a on the vibrator 41 so that at printing operation the vibrator 41 will be raised as 115 shown in Fig. 6 to present the upper ribbon field *a* to the types, the vibrator 40 remaining quiescent in normal position during this 120 operation. If it is desired to make use of the lower ribbon field *b* the finger 56 is switched rightward until the notch 65 engages with the branch 60 to retain the finger 56 underlying the shoulder 53 on the vibra- 125 130

tor 40. With the parts thus set, if the printing keys be operated the vibrator 40 will be raised as shown in Fig. 7 so as to present the ribbon field *b* to the types. During this 5 operation the vibrator 41 will remain quiescent in normal position.

As clearly appears in Fig. 4 the slots 52 so register with one another that there is a central opening, numbered 78 for descriptive purposes, extending to the top of the 10 slot. If the finger 56 be switched until the central notch 64 engages with the branch 60, the finger 56 will be retained in register with the opening 78 so that at printing operation said finger will vibrate up and down in said opening without affecting either of the vibrators which will both remain quiescent in normal position, thus permitting mimeographing to be done. It will be understood further that at ribbon vibrating 15 operation the ribbon guiding device 76 is also vibrated through the lever 73 and the arm 69. The parts, however, are so proportioned and arranged that the vibrating movement of the device 76 is in extent only 20 about one-half as much as the vibrating movement of the vibrators, it being found in practice that this is sufficient and that a greater movement of the device 76 would cause undesirable slack. This vibrating 25 movement is communicated to the device 76 in order to prevent the ribbon from becoming taut and causing too great a strain on the ribbon and too great a consumption of power during vibrating operations. It will be clear that if the guide device 76 were stationary the printing portion 30 of the ribbon at times could not be vibrated to the full extent without stretching the ribbon and also perhaps advancing it longitudinally to the greater or less extent from the paying off spool.

It will be observed that the relationship of the finger 56 with the ribbon triangle is 45 such that the parts coöperate to provide an indicating device. For example, when the finger 56 is switched to the left, as in Fig. 4, it will be close to the black ribbon field *a*, thus indicating that the black field 50 is in use, whereas when the finger 56 is switched to the right as in Fig. 7, it will be nearer the printing field *b*, indicating that this ribbon field is in use.

While I have shown the ribbon triangularly arranged, it will be understood that the principle is adaptable generally to polygonal figures of odd numbers of sides, for example, a pentagonal arrangement may be employed, although of course the triangular 55 disposition is simplest and most convenient. This principle of the triangular or other polygonal arrangement of the printing medium to vary the printing field may also be made use of in another way, as will be understood from Fig. 9. This figure shows a

paper ribbon 79, one face of which *X* is colored black and the opposite face *Y* is colored red. The paper ribbon 79 is arranged triangularly as it would be if mounted on vibrators of the character illustrated 70 in Figs. 4, 6 and 7, and it will be observed that as a consequence the horizontal or printing portions of the paper ribbon 79 are in register but oppositely faced. Considering the forward horizontal printing portion, the face *X* is in view from the front of the machine and the types will contact with this face when it is in use; but the back face *Y* will in consequence be offset on the paper. Similarly, considering 75 the rear printing portion, it will be understood that while the face *Y* is in view the face *X* will off-set on the paper when the rear horizontal printing portion is in use. In other words, by providing a printing medium having its opposite faces differently colored, we may, by the use of my present invention, so arrange and control this medium so as to bring either of the colored 80 faces into use at will to vary the character 85 of the printing. The paper ribbon also acts as an indicator in coöperation with the shifting finger 56, as in the case of the first construction.

My present invention provides ribbon 95 guides for directing the ribbon polygonally or triangularly in the vicinity of the printing point, the triangular portion of the ribbon being disposed wholly at one side of the printing point and in the present instance 100 below the printing point, the triangle being inverted and the upper side being horizontal and comprising a plurality of plies which overlie one another, one ply being inverted with respect to the other so that opposite edge portions of the ribbon are in 105 register in the plies. It will be observed that means are provided including two vibrators for vibrating selected portions of the 110 triangularly maintained part of the ribbon, in the present instance the selected portions being overlapping plies; that the 115 triangularly maintained portion is maintained by guiding devices which comprise two vibrators or vibratory ribbon guides; that the vibrators may be selectively vibrated by devices which in the present instance include a two-part operating lever, one part being swingable laterally on the other to engage alternatively at will with 120 the vibratory guides or vibrators; that all the ribbon guides, including the vibrators so-called, are independent of the ribbon spools; that the guiding means includes a turning bar which is vibratable independently of the two ribbon vibrators proper; that the guiding device or turning bar co-operates with the ribbon during its passage from one of the vibrators proper to the other; that the guiding device vibrates with 125 130

5 whichever of the ribbon vibrators is operative; that the extent of vibration of the guiding device differs from that of the ribbon vibrators, in the present instance being less; that the vibrators proper are arranged in parallelism and the guiding device is in the present instance located below the vibrators proper; and that the guiding device not only guides the ribbon but assists to 10 turn or twist it so that the overlying plies are oppositely faced.

What I claim as new and desire to secure by Letters Patent, is:—

1. In a typewriting machine, the combination of a platen, ribbon guiding mechanism for maintaining the ribbon in the vicinity of the printing point and for directing the ribbon at one side of the platen in a polygonal course of an odd number of 20 sides, and means for controlling said guiding mechanism to present at will opposite edge portions of the ribbon to the types, said means being adjustable independently of movement of said mechanism.

25 2. In a typewriting machine, the combination of ribbon guiding mechanism for directing the ribbon triangularly in the vicinity of the printing point, and means for controlling said guiding mechanism to 30 present at will opposite edge portions of the ribbon to the types.

3. In a typewriting machine, the combination of ribbon guides for maintaining the ribbon in triangular form at one side of the 35 printing point, and means including said guides for vibrating selected portions of the triangularly maintained part of the ribbon.

4. In a typewriting machine, the combination of ribbon guides for maintaining the 40 ribbon in triangular form at one side of the printing point, and means for at will vibrating selected ones of said guides.

5. In a typewriting machine, the combination of a plurality of ribbon vibrators 45 operative with a single ribbon, and means for at will vibrating predetermined ones of said vibrators.

6. In a typewriting machine, the combination of means including two ribbon vibrators for maintaining two printing plies of the same ribbon oppositely faced, and means for vibrating said vibrators separately.

7. In a typewriting machine, the combination of ribbon guides for guiding a plurality of plies of a single ribbon in superposed relationship at one side of the printing point, and means for vibrating said ribbon guides to cover and uncover the 60 printing point with said ribbon plies.

8. In a typewriting machine, the combination of a carriage, ribbon guiding devices supported independently of the carriage and maintaining ribbon plies of the same 65 ribbon in overlying relationship but with

the edge portions of the plies reversed with respect to each other, and means for controlling the guiding devices to present opposite edge portions of the ribbon at will to the types, said means being adjustable independently of movement of said guiding devices. 70

9. In a typewriting machine, the combination of ribbon guides for guiding a plurality of plies of a single ribbon in superposed relationship at one side of the printing point, and means for at will vibrating at printing operation pre-selected ribbon guides to present predetermined plies opposite the printing point. 75

10. In a typewriting machine, the combination of ribbon guides disposed in triangular relationship for guiding plies of a single ribbon in superposed relationship in the vicinity of the printing point but with opposite edge portions of said plies nearest the printing point, and means for vibrating said ribbon plies. 80

11. In a typewriting machine, the combination of ribbon guides disposed in triangular relationship for guiding plies of a single ribbon in superposed relationship in the vicinity of the printing point but with opposite edge portions of said plies nearest the printing point, and means for at will selectively vibrating said guides to present different ribbon plies to the types. 85

12. In a typewriting machine, ribbon guides for directing the ribbon in a triangular course and in superposed plies. 90

13. In a front strike typewriting machine, the combination of a platen and ribbon guides forward of the platen and directing the ribbon in a triangular course, and in superposed plies in the vicinity of the printing point. 95

14. In a typewriting machine, the combination of ribbon spools carrying a single ribbon, ribbon guiding devices independent of said spools and guiding the ribbon in a triangular course at one side of the printing point and so that the ribbon as it winds on and off said spools has its edge portions oppositely disposed, and means for controlling said guiding devices to present at will opposite edge portions of the ribbon to the types. 105

15. In a typewriting machine, the combination of ribbon spools carrying a single ribbon, and ribbon guides directing the ribbon in a triangular course and in superposed plies at one side of the printing point, opposite edge portions of the ribbon overlying one another in said plies. 110

16. In a typewriting machine, the combination of ribbon spools carrying a single ribbon, ribbon guides directing the ribbon in a triangular course and in superposed plies at one side of the printing point, opposite edge portions of the ribbon overlying 115 120 125 130

one another in said plies, and means for vibrating selected guides independently of each other for presenting predetermined ribbon plies to the printing point.

- 5 17. In a typewriting machine, the combination of ribbon spools carrying a single ribbon, ribbon guides independent of said spools and guiding the ribbon in a plurality of superposed plies, ribbon guides directing 10 the ribbon in a triangular course and in superposed plies at one side of the printing point, opposite edge portions of the ribbon overlying one another in said plies, and means for vibrating selected guides independently of each other for presenting opposite edge portions of the ribbon to the printing point.

18. In a typewriting machine, the combination of a plurality of ribbon vibrators, 20 means for selectively vibrating said vibrators at printing operation, and an independent vibratory turning bar.

19. In a typewriting machine, the combination of a plurality of ribbon vibrators 25 operative with a single ribbon, a guiding device for guiding the ribbon in its passage from one of said ribbon vibrators to the other, and means for at will vibrating a predetermined vibrator.

30 20. In a typewriting machine, the combination of a plurality of ribbon vibrators cooperative with a single ribbon, a guiding device for guiding the ribbon in its passage 35 between said ribbon vibrators, and means for at will vibrating a predetermined vibrator and for vibrating said guiding device.

21. In a typewriting machine, the combination of a plurality of ribbon vibrators, an 40 operating lever co-operative at will with a pre-selected vibrator, actuating means for said operating lever, a ribbon guide for guiding the ribbon between said vibrators, and connections between said guide and 45 said actuating means.

22. In a typewriting machine, the combination of ribbon vibrators, key controlled actuating means therefor, and a separate ribbon guide connected with said means, the 50 connection between said vibrators and said means being breakable at will.

23. In a front-strike typewriting machine, ribbon guiding mechanism for directing the ribbon in a triangular course below the 55 printing point.

24. In a front-strike typewriting machine, the combination of ribbon guides for maintaining the ribbon in the form of an inverted triangle below the printing point, and 60 means for selecting and vibrating said guides to employ selected horizontal portions of said triangular part.

25. In a front-strike typewriting machine, the combination of ribbon vibrators for 65 guiding a plurality of plies of a single rib-

bon in superposed relationship below the printing point, and means for selectively vibrating said vibrators to cover and uncover the printing point with the ribbon plies.

26. In a front-strike typewriting machine, 70 the combination of ribbon vibrators for guiding a plurality of plies of a single ribbon in superposed relationship below the printing point, vibrating devices and means for alternatively connecting said vibrators 75 with said devices.

27. In a typewriting machine, the combination of a pair of ribbon vibrators, each vibrator comprising guiding slots for directing a ribbon ply horizontally, a guiding 80 device independent of the two vibrators and guiding the ribbon as it passes from one vibrator to the other, and key controlled actuating means connectible selectively with said vibrators.

28. In a typewriting machine, the combination of a pair of ribbon vibrators, each vibrator comprising guiding slots for directing a ribbon ply horizontally, a guiding 90 device independent of the two vibrators and guiding the ribbon as it passes from one vibrator to the other, and a key controlled operating lever connectible at will with said vibrators alternatively.

29. In a typewriting machine, the combination of a pair of ribbon vibrators, each vibrator comprising guiding slots for directing a ribbon ply horizontally, a guiding 95 device independent of the two vibrators and guiding the ribbon as it passes from one vibrator to the other, an operating lever alternatively connectible with said vibrators, key controlled actuating means for said lever, and connections between said actuating means and said guide.

30. In a typewriting machine, the combination of a pair of ribbon vibrators, each vibrator comprising guiding slots for directing a ribbon ply horizontally, a guiding 100 device independent of the two vibrators and guiding the ribbon as it passes from one vibrator to the other, and a jointed two-part operating lever adjustable at will to connect with one or the other of said vibrators.

31. In a typewriting machine, the combination of a plurality of ribbon vibrators each provided with a shouldered slot, a key controlled operating lever shiftable at will to connect operatively with either of said 110 shouldered slots, said lever being also shiftable to move inoperatively in said slots.

32. In a typewriting machine, the combination of a plurality of ribbon vibrators, a guide for the ribbon between said vibrators, 125 and means for selectively vibrating said vibrators and for constantly vibrating said guide at printing operation, the extent of vibration of said guide differing from the extent of vibration of said vibrator.

33. In a typewriting machine, the combination of a plurality of ribbon vibrators, a guide for the ribbon between said vibrators, and means for selectively vibrating said vibrators and for constantly vibrating said guide at printing operation, the extent of vibration of said guide differing from the extent of vibration of said vibrator, both said vibrators being disconnectible at the

10 same time from said means.

34. In a typewriting machine, the combination of a pair of ribbon vibrators arranged in parallelism and each provided with a shouldered slot, a two-part operating lever, one part being swingable on the other from side to side to engage with the shouldered portions of said slots, and detent devices for maintaining said swingable part in engaging positions.

20 35. In a typewriting machine, the combination of a pair of ribbon vibrators arranged face to face and each provided with a shouldered slot, a two-part operating lever, one part being swingable on the other from side to side to engage with the shouldered portions of said slots, and detent devices for maintaining said swingable part in engaging positions, the detent also operat-

ing to maintain said swingable part in inoperative or disengaged position.

36. In a typewriting machine, the combination of a pair of ribbon vibrators, actuating devices therefor, and a guiding device for guiding and turning the ribbon between said vibrators, the ribbon being turned or twisted so as to present opposite faces of overlying plies for use.

37. In a typewriting machine, the combination of two ribbon vibrators, an operating lever comprising two parts, one part being swingable to engage at will with the vibrators in alternation, a key controlled universal bar, a link connecting said universal bar with said lever, a pivotally supported guiding and turning device coöperating with the bent portion of the ribbon between the vibrators, and a member on said link for actuating said device.

Signed at the borough of Manhattan, city of New York, in the county of New York, and State of New York, this 26th day of May A. D. 1911.

JOHN WALDHEIM.
